US00D819377S

(12) **United States Design Patent** (10) **Patent No.:** **US D819,377 S**
Brown et al. (45) **Date of Patent:** **** Jun. 5, 2018**

(54) **DISPLAY STRUCTURE**

- (71) Applicant: **Apple Inc.**, Cupertino, CA (US)
(72) Inventors: **Sam Brown**, Sunnyvale, CA (US);
Casey Feeney, Los Gatos, CA (US);
Jean-Marc Gady, Los Altos, CA (US);
Christopher M. Green, Woodside, CA (US);
Kully Kraig Mandon, San Francisco, CA (US)
(73) Assignee: **Apple Inc.**, Cupertino, CA (US)
(**) Term: **15 Years**
(21) Appl. No.: **29/601,149**
(22) Filed: **Apr. 19, 2017**

Related U.S. Application Data

- (63) Continuation of application No. 29/537,122, filed on Aug. 21, 2015, now Pat. No. Des. 785,978, and a continuation of application No. 29/556,111, filed on Feb. 26, 2016, and a continuation of application No. 29/556,133, filed on Feb. 26, 2016, said application No. 29/556,111 is a continuation of application No. 29/537,122, filed on Aug. 21, 2015, now Pat. No. Des. 785,978.

(57) **CLAIM**

The ornamental design for a display structure, as shown and described.

DESCRIPTION

FIG. 1 is a top right perspective view of a display structure showing the claimed design; and,
FIG. 2 is a front view thereof.

The dashed broken lines in the figures show portions of the display structure that form no part of the claimed design. The dot-dash broken lines in the figures show boundaries that form no part of the claimed design. Portions of the display structure not shown form no part of the claimed design.

1 Claim, 2 Drawing Sheets

FIG. 2

UNITED STATES PATENT AND TRADEMARK OFFICE
CERTIFICATE OF CORRECTION

PATENT NO. : D819,377 S
APPLICATION NO. : 29/601149
DATED : June 5, 2018
INVENTOR(S) : Brown et al.

Page 1 of 1

It is certified that error appears in the above-identified patent and that said Letters Patent is hereby corrected as shown below:

In the "Related U.S. Application Data" Item (63), replace:

"Continuation of application No. 29/537,122, filed on Aug. 21, 2015, now Pat. No. Des. 785,978, and a continuation of application No. 29/556,111, filed on Feb. 26, 2016, and a continuation of application No. 29/556,133, filed on Feb. 26, 2016, said application No. 29/556,111 is a continuation of application No. 29/537,122, filed on Aug. 21, 2015, now Pat. No. Des. 785,978."

With:

-- "Continuation of application No. 29/537,122, filed on Aug. 21, 2015, now Pat. No. Des. 785,978, and a continuation of application No. 29/556,111, filed on Feb. 26, 2016, and a continuation of application No. 29/556,133, filed on Feb. 26, 2016, said application No. 29/556,111 is a continuation of application No. 29/537,122, filed on Aug. 21, 2015, now Pat. No. Des. 785,978, and said application No. 29/556,133 is a continuation of application No. 29/537,122 filed on Aug. 21, 2015, now Pat. No. Des. 785,978." --.

Signed and Sealed this
Fourth Day of September, 2018

Andrei Iancu
Director of the United States Patent and Trademark Office
